CLAIM

The ornamental design for a mounting bracket detachable leg, as shown and described.

DESCRIPTION

FIG. 1 is a perspective of a mounting bracket detachable leg according to the present design;

FIG. 2 is a front view of the detachable leg of FIG. 1;

FIG. 3 is a right side view of the detachable leg of FIG. 1;

FIG. 4 is a top view of the detachable leg of FIG. 1;

FIG. 5 is a rear view of the detachable leg of FIG. 1;

FIG. 6 is a left side view of the detachable leg of FIG. 1; and,

FIG. 7 is a bottom view of the detachable leg of FIG. 1.

The broken lines in the drawings depict portions of the

article and form no part of the claimed design.
